(57) **CLAIM**

The ornamental design for a bobbin, as shown and described.

DESCRIPTION

FIG. 1 is a perspective view of a bobbin showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is a cross-sectional view taken along the line A-A of FIG. 6;

FIG. 9 is the second perspective view showing the bobbin; and,

FIG. 10 is a third perspective view shown in environmental use.

The broken lines in the figures illustrate the portions of the design that form no part of the claimed design.
